COMBINED COMPUTER-DIRECTED DRAWING
INSTRUMENT CONSOLE AND DRAWING
BOARD

George E. Eaton, Charles H. Hartman, and Talmage O.
McCartney, all of Seattle, Wash., assignors to Perspec-
tive, Inc., Seattle, Wash., a corporation of Washington

Filed Mar. 15, 1965, Ser. No. 84,269

Term of patent 14 years

(Cl. D33—14)

Fig. 1.

Fig. 2.

Fig. 3.

FIGURE 1 is a top front perspective view of a combined computer-directed drawing instrument console and drawing board showing our new design.

FIGURE 2 is an end elevational view thereof.

FIGURE 3 is a top rear perspective view thereof.

The dominant features of our design reside in the full-line portions of the drawings.

We claim:

The ornamental design for a combined computer-directed drawing instrument console and drawing board, substantially as shown and described.
